Specification of Letters Patent.

Patented Dec. 2, 1913.

Application filed November 4, 1912. Serial No. 729,272.

To all whom it may concern:

Be it known that I, GEORGE M. BRECKENRIDGE, a citizen of the United States, and a resident of the city of Chicago, county of Cook, and State of Illinois, have invented certain new and useful Improvements in Printing-Machines, of which the following is a specification.

My invention relates to printing mechanism and more especially to printing mechanism or apparatus employed for printing indorsements on checks, and has for its object the provision of a machine of this character which is of improved construction and operation.

The invention consists in the combinations and arrangements of parts hereinafter described and claimed.

The invention will be best understood by reference to the accompanying drawings forming a part of this specification, and in which,

Figure 1 is a side view of a machine embodying my invention, Fig. 2, an enlarged detail section taken through clutch mechanism employed in the machine, Fig. 3, an enlarged view of an electric switch member employed in the machine, Fig. 4, a top plan view of the machine with portions broken away for the sake of clearness, Fig. 5, a front elevation of the machine, Fig. 6, an enlarged section of a printing roller employed in the machine, Fig. 7, an enlarged section of an electric switch employed in the machine, Fig. 8, a detail view of a stop member employed in the machine, Fig. 9, a longitudinal section of the machine, Fig. 10, a side view of a modified form of clutch mechanism, and Fig. 11, an inner face view of said clutch mechanism.

The preferred form of construction as illustrated in the drawings comprises a suitable frame 1 having an ordinary electric motor 2 mounted therein. Motor 2 is connected in circuit, by means of wires 3, 4 and 5, with switch plates 6 and 7 which are insulated from each other and secured to the side of frame 1, as indicated, said switch plates 6 and 7 being arranged at an inclination to each other so as to afford a sort of wedging action to the other member of the

switch, as will be explained hereinafter. Motor 2 is connected by means of a belt 8 with a driving pulley 9 which is secured to a driving shaft 10 suitably mounted in the machine. Driving shaft 10 is connected by means of a belt 11 with a driving pulley 12 mounted upon a printing shaft 13 arranged centrally in the machine, as indicated. This printing shaft 13 has two disks 14 adjustably secured thereto by set screws and said disks are provided with suitable perforations adapted to receive pins 15 on a segmental supporting member 16. Segmental member 16 is provided with inwardly extending arms 17 which are notched or bifurcated at their inner ends to embrace shaft 13, and the printing element 18 is secured to the outer surface of said member 16 as indicated in Fig. 6. This specific form of construction of a printing member constitutes a simple and efficient one for the purpose and one that may be readily taken apart and reassembled as desired. An impression roller 19 is mounted in spring held slideable blocks 20 so as to have yielding contact with said printing member and an inking roller 21 is also mounted in a spring held slideable block 22 so as to have yielding contact with said printing member.

A stationary guide member 23 is arranged above the printing mechanism and extends substantially vertically as indicated in Fig. 9. A movable guide member 24 is also mounted above the printing mechanism to co-operate with guide 23, said movable guide member 24 extending in an inclined position upwardly and toward the operator of the machine, who stands to the left thereof, as the machine is shown in Fig. 9. The guide member 24 is pivotally mounted on downwardly and rearwardly extending arms 25 which are pivotally mounted on shaft 13. By this arrangement it will be observed that when the operator inserts a check between guide members 23 and 24, the natural downward movement of the hand will bring the hand in contact with guide member 24 and depress the same after the check has been inserted in operative position between roller 19 and the printing roller, thus insuring that the guide member will be de-

pressed when all checks inserted are in the same relative position with respect to the printing mechanism. Inasmuch as guide member 24 controls the operation of the machine, as will be explained hereinafter, this insures uniformity of work. A suitable supporting table 26 is arranged forward of guide member 24 and a suitable discharge slide 27 is arranged to guide the marked or indorsed checks into a receptacle 28 therefor.

A spring-held clutch arm 29 is secured to the end of shaft 13 just outside of pulley 12 and is provided with a locking pin 30 which is adapted to enter any one of a plurality of holes 31 formed in the outer face of a plate 32 on the outer face of pulley 12. An automatic stop member 33 is pivotally mounted on frame 1 and is normally held by a spring 34 in the path of clutch arm 29 so as to be struck by said clutch arm when the shaft 13 revolves. Stop member 33 is outwardly beveled or rounded at its forward end 35 and an abrupt stop shoulder 36 is formed at the termination of bevel 35 as shown in Fig. 8. By this arrangement it will be observed, that as shaft 13 and pulley 12 revolve in the direction of the arrow shown in Fig. 1, the upper end of arm 29 will strike the beveled portion 35 of stop member 33 and said arm will be forced outwardly to disengage pin 30 from the corresponding hole 31, thus disengaging pulley 12 from shaft 13. Immediately after this is effected, arm 29 strikes the abrupt stop shoulder 36 and stops shaft 13 and consequently the printing mechanism in the same position every time. The adjacent supporting arm 25 for guide member 24 is provided with a spring-held extension 37 which in turn is connected by means of a link 38 with stop member 33, so that when said guide member 24 is depressed, stop member 33 will be swung upwardly to release clutch arm 29 to permit rotation of shaft 13. Thus, it will be observed, that at each insertion of a check in the printing mechanism, the guide member 24 will be depressed by the natural motion of the operator's hand, and printing shaft 13 released for operation. At its rear end extension 37 carries a pivoted trigger member 39 normally held against a stop pin 40 by means of a spring 41. This trigger member 39 is arranged to contact with one arm 42 of a spring-held bell crank so as to rock said bell crank upon elevation of said trigger arm, but to pass said bell crank idly when depressed. The other arm 43 of said bell crank is connected by means of a link 44 with one arm 45 of another larger bell crank as shown in Fig. 1. Arm 45 carries metallic spring switch members 46, said switch members being secured to said arm by means of insulating members 47, and cooperates with switch plates 6 and 7, as indicated in Fig. 7. The other arm 48 of said larger bell crank

is bent outwardly, as shown in Fig. 4, and its forward end is set in the path of a pin 49 carried by an arm 50 secured to the corresponding end of shaft 13. By this arrangement it will be observed that upon depression of guide member 24, the rear end of extension 37 is elevated to release shaft 13 and simultaneously operate switch members 46 to close the electric circuit for motor 2, and that upon release of guide member 24, trigger member 39 will pass lever arm 42 without affecting the same, thus maintaining a closed circuit until otherwise disturbed. This action releases clutch arm 29 from stop member 33 and at the same time closes the circuit for motor 2 to start the machine and complete the marking or printing on the check, and discharge the same into receptacle 28. As shaft 13 continues to revolve pin 49 strikes the forward end of lever arm 48 and throws switch members 46 rearwardly to break the circuit for motor 2. Immediately after the circuit of motor 2 is broken clutch arm 29 comes in contact with stop member 33, which in the meantime has returned to normal position, and is disengaged from pulley 12 and positively stopped by shoulder 36, thus stopping the printing mechanism in the same position each time. However, owing to the high speed of the motor and the inertia of the parts, the pulley 12 and intermediate connections with said motor are free to revolve under their inertia, thus avoiding sudden stops and shocks to the motor. Thus, it will be observed, that the motor is stopped between each operation of the machine and the flow of current entirely cut off during this period. Inasmuch as the time consumed by the operator in placing a check in the machine is usually considerably longer than the time actually employed by the machine in this operation, this effects a considerable saving in power. In order to accommodate checks or slips of greater length the frame 1 is provided with a lateral extension 1'. 100

The modified form of construction illustrated in Figs. 10 and 11 comprises a cam member 51 having a stop shoulder 51' secured to the inner face of pulley 12. A spring-held stop pawl 52 is pivotally mounted on the frame and given a slot-and-pin connection 53 with guide member 24. Stop pin 30 is secured directly to the outer face of pulley wheel 12 and pulley wheel 12 is fixed to shaft 13. By this arrangement, it will be observed, that upon depression of guide member 24, stop pawl 52 will be operated to release cam 51 and consequently shaft 13 for operation by the motor, otherwise the construction is identical with that illustrated in the other figures described above. 115

While I have illustrated and described the preferred forms of construction for carry- 120

ing my invention into effect, these are capable of variation and modification without departing from the spirit of the invention. I, therefore, do not wish to be limited to the 5 precise details of construction set forth, but desire to avail myself of such variations and modifications as come within the scope of the appended claims.

Having described my invention what I 10 claim as new and desire to secure by Letters Patent is:

1. A machine of the class described comprising rotary printing mechanism and an electric motor for operating the same; a 15 circuit for operating said motor; automatic means for breaking said circuit and disconnecting said printing mechanism; and an automatic stop arranged to stop said printing mechanism at the same point after 20 each operation thereof, substantially as described.

2. A machine of the class described comprising printing mechanism and an electric motor for operating the same; a circuit for 25 operating said motor; automatic means for first breaking said circuit and then disconnecting said printing mechanism and motor after each operation of said printing mechanism; and an automatic stop arranged to 30 stop said printing mechanism at the same point after each operation thereof, substantially as described.

3. A machine of the class described comprising rotary printing mechanism and an 35 electric motor for operating the same; an electric circuit for operating said motor; a switch controlling said circuit; a clutch mechanism for releasably connecting said motor and printing mechanism; means for 40 connecting said clutch mechanism and throwing said switch to close said circuit; and automatic means for throwing said switch to break said circuit and disconnecting said clutch mechanism, substantially 45 as described.

4. A machine of the class described comprising printing mechanism and an electric motor for operating the same; an electric circuit for operating said motor; a switch 50 controlling said circuit; a clutch mechanism for releasably connecting said motor and printing mechanism; means for connecting said clutch mechanism and throwing said switch to close said circuit; and automatic 55 means for first throwing said switch to break said circuit and then disconnecting said clutch mechanism, substantially as described.

5. A machine of the class described comprising rotary printing mechanism and an 60 electric motor for operating the same; an electric circuit for operating said motor; a switch controlling said circuit; a clutch mechanism for releasably connecting said 65 motor and printing mechanism; means for

simultaneously connecting said clutch mechanism and throwing said switch to close said circuit; and automatic means for throwing said switch to break said circuit and disconnecting said clutch mechanism, 70 substantially as described.

6. A machine of the class described comprising printing mechanism and an electric motor for operating the same; an electric circuit for operating said motor; a switch 75 controlling said circuit; a clutch mechanism for releasably connecting said motor and printing mechanism; means for simultaneously connecting said clutch mechanism and throwing said switch to close said circuit; and automatic means for first throwing said switch to break said circuit and then disconnecting said clutch mechanism, 80 substantially as described.

7. A machine of the class described comprising rotary printing mechanism and an electric motor for operating the same; an electric circuit for operating said motor; a switch controlling said circuit; a clutch mechanism for releasably connecting said motor and printing mechanism; means for connecting said clutch mechanism and throwing said switch to close said circuit; and automatic means for throwing said switch to break said circuit and immediately 90 release said switch to permit independent operation thereof and disconnecting said clutch mechanism, substantially as described.

8. A machine of the class described comprising printing mechanism and an electric motor for operating the same; an electric circuit for operating said motor; a switch controlling said circuit; a clutch mechanism for releasably connecting said motor and printing mechanism; means for simultaneously connecting said clutch mechanism and throwing said switch to close said circuit; and automatic means for first throwing said switch to break said circuit and immediately 100 release said switch to permit independent operation thereof and then disconnecting said clutch mechanism, substantially as described.

9. A machine of the class described comprising rotary printing mechanism and a driving shaft therefor; a driving member loosely mounted on said shaft; a clutch member fixed to said driving member and provided with a plurality of holes arranged 115 circumferentially with the axis of said shaft as a center; a spring held arm fixed to said shaft adjacent said clutch member; a pin on said arm arranged to enter said holes; a stop member having a beveled surface and an abrupt stop shoulder arranged to strike said arm; an electric motor arranged to drive said driving member; an electric circuit for operating said motor; a switch controlling said circuit; means for simultaneous 120

120

125

130

ously moving said stop member to release said arm and throwing said switch to close said circuit; and automatic means for opening said switch before contact between said arm and said stop member, substantially as described.

In testimony whereof I have signed my

name to this specification in the presence of two subscribing witnesses.

GEORGE M. BRECKENRIDGE.
